(57) **CLAIM**

The ornamental design for a door and ceiling frame component, as shown and described.

DESCRIPTION

FIG. 1 is a top front perspective view of a door and ceiling frame component showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan elevational view thereof.

The symbolic breaks shown in the drawings indicate that any portion of the article between the break lines forms no part of the claimed design.

1 Claim, 5 Drawing Sheets(56)
